(57) **CLAIM**

The ornamental design for a roof mount bracket for mounting solar panels, as shown and described.

DESCRIPTION

FIG. 1 is a front isometric view of the roof mount bracket for mounting solar panels showing our new design;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines represent structures or features that form no part of the claim design. The roof mount bracket for mounting solar panels is shown with a symbolic break in its length. The appearance of any portion of the article between the break lines forms no part of the claimed design.
